CLOSURE FOR FLEXIBLE TUBE CONTAINERS

Application filed November 29, 1929. Serial No. 410,519.

This invention relates generally to containers for paste, and particularly to tubular containers of flexible materials such as are used for tooth paste and similar plastic substances.

The main object of this invention is to provide an exceedingly simple and efficient form of closure for flexible tube containers.

The second object is to produce a closure 10 which will be commercially practical on account of its simple construction and ease of manufacture and assembly.

The third object is to produce a closure for tooth paste tubes and similar devices in which 15 the cap or closure cannot become lost or separated from the container itself.

The fourth object is to reduce the amount of time required for opening and closing the container.

20 These, and other objects, will become more apparent from the specification following as illustrated in the accompanying drawings, in which:

Figure 1 is a plan of the device showing 25 same in a closed position.

Figure 2 is a fragmentary side elevation of the container showing the closure broken away in section.

Figure 3 is a fragmentary end elevation of 30 the closure and tube.

Figure 4 is a side elevation of the device in an open position.

Figure 5 is an enlarged side elevation of 35 the closure showing a slightly modified form of spring arm.

Similar numbers of reference refer to similar parts throughout the several views.

Referring in detail to the drawings, there 40 is shown the usual form of cylindrical paste container 10 whose discharge end 11 is somewhat bulging and has projecting therefrom a tapering outlet 12 such as are commonly provided on tooth paste tubes, except that in this case the outlet is not necessarily threaded. On one side of the end 11 is formed an eye 13 and on the opposite side thereof is formed a hook 14 preferably cast integral with the metal of the end 11 and the outlet 12.

45 The container itself consists of a cap 15

whose interior 16 is tapered to conform with the outlet 12. The cap 15 is preferably provided with a cork insert 17 for the purpose of providing a better seal for the outlet 12. On the top of the cap 15 is formed an eye 55 18 through which passes a spring wire cap-holding clamp 19 whose end 20 is in the form of an eye which hinges on the eye 13, and whose end 21 is also in the form of a closed eye preferably larger than the end 20 to permit same to be used as a handle, and also to facilitate its engagement with the hook 14.

In the modification shown in Figure 5 the clamp 19 is provided at its mid portion with a loop 22 which passes through the eye 18, 60 its function being to definitely locate the cap 15 at the center of the clamp 19. Obviously, any other means for accomplishing this cap locating object could be employed without departing from the spirit of this invention. 70

The operation of the device is as follows: 75 In order to open the container it is merely necessary to move the end 21 to one side in a manner to disengage the hook 14 and swing the entire clamp and closure to the position shown in Figure 4, or still further if desired, giving free access to the paste in the container. To close same a simple reverse operation is all that is necessary, namely bringing the end 21 back into engagement with the hook 14. 80

The shape of the clamp 19 is such as to require a tension to be placed thereon when in a closed position, thereby holding the cap 85 15 under a spring tension.

It is a well known fact that a great number of devices have been constructed for this purpose, these having failed to find their way into the market due to their complicated nature or manufacture or operation, but mostly on account of their first cost. With a tooth paste tube particularly it is desirable to prevent the closure from becoming lost or separated from the container when using same, and it is equally desirable when not in use that the closure will be properly placed in position. It is for this purpose that we have provided the simple mechanism illustrated in the drawings which will require but a 100

touch of the finger to close or open the container.

We claim:

1. The combination of a flexible tube container having an outlet projecting from one end thereof, a cap slidably mounted on said outlet, a spring clamp hinged to said container at one end and hooked to said container at the other end, the intermediate portion of said clamp hingedly bearing against said cap.
2. In a tooth paste container the combination of a tubular flexible container having an outlet projecting from the middle of one end thereof, an eye formed on one side of said outlet and a hook on the other side thereof, a closure for said outlet, and a clamp hinged to said eye and latched under said hook having its intermediate portion hingedly attached to said cap.
3. In a paste holder the combination of a tubular flexible container having an outlet projecting from the middle of one end thereof having an eye formed on one side of said outlet end and a hook on the other side thereof, a closure for said outlet having an eye formed in the middle of its outlet end, a spring wire clamp whose intermediate portion passes loosely through said closure eye, each end of said spring wire clamp having its tip closed upon itself in a manner to form a loop at each end of said clamp, one of said loops permanently engaging the eye on the end of the container and the other loop latching under said hook.
